WEFT CARRIER

George A. Irons, Jr., Worcester, Mass., assignor to Crompton & Knowles Loom Works, Worcester, Mass., a Corporation of Massachusetts

Application July 10, 1931. Serial No. 549,964

15 Claims. (Cl. 139—267)

This invention relates to improvements in weft carriers for looms and it is the general object of the invention to improve carriers so that at the time of transfer there will be reduced likelihood of thread breakage.

In the ordinary bobbin changing shuttle there is a spring which holds the ringed butt end of the bobbin and there is also provided an inclined guide which directs the incoming bobbin toward the spring. Due to the fact that the shuttle may not always register accurately with the transfer mechanism it is necessary to guide the incoming bobbin to its correct position in the shuttle. When the weft is led through the hollow barrel of the bobbin so as to be discharged at the butt end it is likely to lie across the inclined or cam guide, and when the ordinary form of bobbin is employed there is likelihood that the thread will be pinched or cut on the guide. It is an important object of my present invention to provide the bobbin with a guide engaging surface which is notched so that the thread can find its position in one of the notches while the guide engages projections on the bobbin which define the notches.

It is a further object of my invention to provide two cooperating parts one on the bobbin and one on the shuttle adapted to effect proper relative position of the bobbin and shuttle, one of said parts being so formed as to permit the placing of the weft out of reach of the other part at the time of transfer. In carrying this broader phase of my invention into effect I may provide either the bobbin or the guide with notches or grooves.

With these and other objects in view which will appear as the description proceeds, my invention resides in the combination and arrangement of parts hereinafter described and set forth in the claims.

In the accompanying drawing, wherein I have shown two forms of my invention,

Fig. 1 is a top plan view of a shuttle having the preferred form of the invention shown therein, the bobbin being substantially exhausted.

Fig. 2 is a view taken in the direction of arrow 2, Fig. 1 showing a full bobbin being forced down on the empty one.

Fig. 3 is a transverse section on line 3—3 of Fig. 2,

Fig. 4 is a view similar to Fig. 1, but showing a modified form of the invention with grooves in the guide,

Fig. 5 is a transverse vertical section on line 5—5 of Fig. 4,

Fig. 6 is a diagrammatic view showing a transfer mechanism in the loom and suggesting the manner of use of my invention.

Referring to Figs. 1, 2 and 3, I have shown a shuttle S having a weft chamber 10 and a bobbin gripping spring 11. The latter has a pair of arms 12 and 13 each notched to receive the rings 14 of the head or butt 15 of a bobbin B. The latter is provided with a bore 16 and a preferably conical tip 17.

A guide 18 is secured by means of screw 19 in a recess 20 in the upper face of the shuttle, and said guide has a downwardly inclined surface 21 positioned to engage an incoming bobbin and direct the same so that the rings thereof will be in register with the notches of the arms 12 and 13.

The weft W of the bobbin in the shuttle may be led through the conical tip 17 and back through the bore 16 so that it emerges from the end of the bore 22 at the butt end of the bobbin. The loom has a transfer arm T to push a full bobbin into the shuttle and the latter is supported on a lay L. The matter thus far described of itself forms no part of my present invention.

In carrying my improvements into effect I employ two different arrangements of parts, the preferred form of which is shown in Figs. 1, 2, and 3 and consists of providing the butt of the bobbin with a series of projections 30 rounded on their outer ends and defining between them notches 31. The upper surface of the incline 21 may be flat as in the usual automatic shuttle and the weft may extend thereover as suggested in Fig. 2.

In operation, the full bobbin B' will be forced downwardly by the transfer mechanism T and if the shuttle is somewhat misplaced in its box the butt of the bobbin will descend downwardly along a path which will intersect the inclined surface 21. When the incoming bobbin strikes the guide it will engage the guide along one or two of the projections 30, and the thread will lie in one of the notches. I have found by making the projections rather small but rounded that considerable space is provided for the weft, and cutting of the latter is practically eliminated.

In the modified form shown in Figs. 4 and 5 the usual form of bobbin 40 is used with a rounded end 41, and the grooves 42 are cut in the guide to form ribs 43 as shown in Fig. 4. The thread as it issues from the butt end of the bobbin 40 extends over the guide and is likely to lie in one or another of the grooves, so that

when a new bobbin 44 is moved downwardly along the inclined guide it will not be able to reach the thread, but will be supported by one or more of the ribs which define the grooves.

5. From the foregoing it will be seen that I have provided means for preventing cutting engagement between the weft and the incoming bobbin. In one instance the butt of the bobbin is provided with a series of rounded projections 10 defining notches, the projections sliding along a guide and the thread lying in one or another of the notches. In the other instance ribs on the guide support the bobbin and define grooves one of which receives the weft to prevent cutting 15 thereof. It is to be understood that the weft extending from the spent or expelled bobbin back to the cloth is severed at the selvage so that it is carried out of the shuttle box by the outgoing bobbin. By the use of my invention 20 the weft end is not severed at the shuttle and assurance is given that it will be drawn out with the bobbin which is discharged at the time of transfer.

Having thus described my invention it will be 25 seen that changes and modification may be made therein by those skilled in the art without departing from the spirit and scope of the invention and I do not wish to be limited to the details herein disclosed, but what I claim is:

30 1. In a loom, a shuttle, a spent bobbin therein from which extends a weft thread, a guide member on the shuttle across which the weft thread extends, and a weft carrying member to engage the guide member and enter the shuttle, one of said members having a notch positioned to receive the weft to prevent cutting thereof when the members engage each other.

40 2. In a loom, a shuttle, a bobbin guide thereon, a bobbin with a butt held in the shuttle and having a weft extending over the guide, a second bobbin to move down along the guide into the shuttle to expel the first named bobbin, and projections on the second bobbin to engage the guide and separated by notches, the weft of the first bobbin lying in one of the notches to avoid 45 cutting and the projections engaging the guide to direct the movement of the second bobbin into the shuttle.

50 3. In a loom, a shuttle, a spent bobbin therein from which extends a weft thread, a guide on the shuttle across which the weft thread lies, a second bobbin to replace the first, and a series of projections arranged around the butt end of the second bobbin and separated by notches, the 55 guide to engage a projection to direct the movement of the second bobbin and the thread lying in one of the notches to prevent cutting thereof when the guide and second bobbin engage each other.

60 4. In a loom, a shuttle, a spent bobbin therein from which extends a weft thread, a bobbin guide on the shuttle over which the weft lies, and means to move a second bobbin into the shuttle along and in contact with the guide and out of contact with the weft.

5. In a loom, a shuttle, a spent bobbin therein from which extends a weft thread, a bobbin guide on the shuttle over which the weft lies, and means to move a second bobbin into the shuttle along and in contact with the guide and out of cutting engagement with the weft. 80

6. In a loom, a shuttle having a downwardly inclined bobbin guide over which extends a weft thread, a bobbin movable along the guide into the shuttle, and means to establish engagement 85 between the bobbin and guide at spaced points laterally of the weft thread.

7. In a loom, a shuttle having a downwardly inclined bobbin guide over which extends a weft thread, ribs on the guide defining grooves in one 90 of which the weft thread lies, and a bobbin movable along the ribs out of engagement with the weft and into the shuttle.

8. In a loom, a shuttle having a downwardly inclined bobbin guide over which extends a weft 95 thread, a bobbin having a butt, and means on the butt defining alternate projections and notches, the projections movable along the guide to direct the bobbin into the shuttle, and the weft lying in one of the notches. 100

9. In a loom, a shuttle having a downwardly inclined bobbin guide over which extends a weft thread, a bobbin having a butt, and means on the butt defining alternate projections and notches, the projections movable along the guide 105 to direct the bobbin into the shuttle, and the weft lying between adjacent projections.

10. In a loom, a shuttle having a downwardly inclined bobbin guide over which extends a weft thread, a bobbin having a butt, and means on the butt defining spaced projections, the projections movable along the guide to direct the bobbin into the shuttle, and the weft lying between adjacent projections. 110

11. A weft bobbin for a shuttle having a bobbin 115 guide, the bobbin having spaced projections defining a series of notches, the projections so constructed as to be movable along the guide while the parts of the bobbin between the projections remain out of contact with the guide. 120

12. A weft bobbin for a shuttle having a bobbin guide, the bobbin having peripherally arranged spaced projections defining notches between them, the projections to engage the guide and the parts of the bobbin between the projections to remain out of contact with the guide, 125 the notches being of less width than the guide.

13. In a shuttle for a bobbin changing loom, a bobbin guide to direct a bobbin into the shuttle, and spaced ribs on the guide defining grooves 130 in said guide.

14. In a shuttle for a bobbin changing loom, a bobbin guide to direct a bobbin into the shuttle, and spaced ribs on the guide defining grooves 135 disposed longitudinally of the axis of the shuttle.

15. A weft bobbin the butt of which is formed with a series of peripherally arranged thread receiving notches located between rounded thread deflecting projections. 140
